(57) **CLAIM**

The ornamental design for a remote control, as shown and described.

DESCRIPTION

FIG. 1 is a top perspective view of the remote control in an open position;

FIG. 2 is a side perspective view of the remote control in an open position;

FIG. 3 is a side perspective view of the remote control in an open position;

FIG. 4 is an end perspective view of the remote control in an open position;

FIG. 5 is an end perspective view of the remote control in an open position;

FIG. 6 is a top perspective view of the remote control in an open position;

FIG. 7 is a bottom perspective view of the remote control in an open position;

FIG. 8 is a bottom perspective view of the remote control in an open position;

FIG. 9 is a top perspective view of the remote control in an open position;

FIG. 10 is a side perspective view of the remote control in an open position;

FIG. 11 is a side perspective view of the remote control in an open position;

FIG. 12 is an end perspective view of the remote control in an open position;

FIG. 13 is an end perspective view of the remote control in an open position;

FIG. 14 is a top perspective view of the remote control in an open position;

FIG. 15 is a bottom perspective view of the remote control in an open position;

FIG. 16 is a bottom perspective view of the remote control in an open position;

FIG. 17 is a top perspective view of the remote control in a closed position;

FIG. 18 is a side perspective view of the remote control in a closed position;

FIG. 19 is a side perspective view of the remote control in a closed position;

FIG. 20 is an end perspective view of the remote control in a closed position;

FIG. 21 is an end perspective view of the remote control in a closed position;

FIG. 22 is a top perspective view of the remote control in a closed position;

FIG. 23 is a bottom perspective view of the remote control in a closed position; and,

FIG. 24 is a bottom perspective view of the remote control in a closed position.
